DESIGN FOR A VELOCIPED FRAME MEMBER

Bert J. Anderson, Hammond, Ind.

Application December 15, 1934, Serial No. 54,438

Term of patent 14 years

To all whom it may concern:

Be it known that I, Bert J. Anderson, a citizen of the United States, residing at Hammond, in the county of Lake and State of Indiana, have invented a new, original, and ornamental Design for a Velocipede Frame Member, of which the following is a specification, reference being had to the accompanying drawing, forming part thereof.

Figure 1 is a side elevation of the velocipede frame member of this invention.

Figure 2 is a top plan view of the velocipede frame member, and shows in particular the bullet-like head and the long tapering streamlined body.

Figure 3 is a perspective view of the velocipede frame member, showing my new design.

I claim:

The ornamental design for a velocipede frame member, as shown and described.

BERT J. ANDERSON.
